LOUIS JULIUS STAMBOIS, DECEASED, LATE OF LONDON, ENGLAND, BY DAVID STAMBOIS
AND REBECCA STAMBOIS, ADMINISTRATORS, BOTH OF LONDON, ENGLAND; AND
ARTHUR ABRAHAM STAMBOISE, OF LONDON, ENGLAND

VULCANIZER

Application filed March 21, 1929, Serial No. 348,935, and in Great Britain April 24, 1928.

This invention is for improvements in or relating to vulcanizers, and has for its main object to provide an improved construction of portable vulcanizer which can be readily manipulated and can be manufactured at a low cost.

According to the primary feature of the invention, there is provided a vulcanizer comprising in combination an arched casing, the upper face of which constitutes one face of a clamp for the article to be vulcanized, heating means (e. g. a detachable heating lamp) adapted to be received under the casing in a position to heat the upper portion of the arch, an abutment member carried by said casing and situated opposite to, but spaced away from, the upper face of the casing, a presser member having a face opposed to the upper face of the arch, a screwthreaded press rod carried (e. g. pivotally by the presser member), and a nut movable on the press rod between the abutment and the presser member and adapted to co-act with said abutment for forcing the presser member towards the upper face of the arch to clamp the article to be vulcanized.

According to another feature of the invention, the said abutment member is in the form of a bar having between its ends a hole into which the press rod extends, which bar constitutes part of an inverted U-shaped yoke mounted on the casing.

Preferably the abutment member constitutes a detachable part of the yoke which is preferably detachably mounted on the casing.

For a better understanding of these and other features of the present invention two embodiments thereof will now be described by way of example only, with reference to the accompanying drawings, in which:

Figure 1 is a perspective view showing one construction of the vulcanizer,

Figure 2 is a fragmentary view of a detail 45 of the vulcanizer shown in Figure 1,

Figures 3 and 4 show the lamp of the vulcanizer in perspective and in section respectively, and

Figure 5 is a perspective view showing a second construction of vulcanizer.

Like reference numerals indicate like parts throughout the figures of the drawings.

Referring first to Figures 1 to 4, the vulcanizer comprises a main rectangular casing 10 in the form of an arch which may be a pressing or a single casting, for example of aluminium; the casing is open at the bottom and has sloping front and back walls 11 and two side walls 12, which walls are closed by a top plate 13. The front and back walls are continuous from the top to the bottom, but the side walls are cut away at 14 to permit of the insertion of a lamp 15 under the casing and to admit air to support combustion. The front and back walls have outwardly extending flanges 23 which may have perforations for the reception of screws whereby the vulcanizer may be secured in position on a table or the like. The lamp 15 is received to slide on shelves 16, which are provided inside the casing on the inner faces of the front and rear walls 11 thereof. These shelves extend from the outside of one side wall to about the middle of the length of the vulcanizer where they terminate in upwardly extending abutments 17. Immediately adjacent the abutments the shelves are formed with recesses 18. The lamp is provided with a handle 19 and with two projections 20 formed on its under surface towards its 80 sides, which projections are adapted to interlock with the recesses aforesaid when the lamp is in its operative position. This is for the purpose of resisting endwise displacement of the lamp along the 85 shelves but the arrangement is such that an operator can easily lift the lamp to disengage the projections and recesses, after which the endwise movement of the lamp can be easily effected. The lamp is formed with an open 90

recess 21 to receive the combustible. The recess has an inwardly directed flange 22 around it adjacent to and below the top of the lamp and the material of the lamp between the flange and the top is undercut. When liquid such as methylated spirit is being burnt this arrangement will be found to preclude the fuel from spreading over the upper surface of the lamp when alight and thus dissipating the heat and giving risk of fire.

Two upstanding supports 24 are mounted on the top plate 13 of the casing. The lower end 25 of each support is bent so as to extend at right angles to the general direction of the support and the ends 25 are each formed with a key hole slot 26 for engagement with a headed pin 27 projecting downwardly from the lower face of the top plate 13 (see Figure 2). Towards its upper end each support is formed with an open ended slot 28. These supports are similar to one another and the slots 28 extend to corresponding edges of both of them. It follows, therefore, that, when the supports are mounted on the casing as shown in Figure 1 so that they face one another, the slots 28 are facing in opposite directions and preferably, for a reason to be explained later, they face in the directions illustrated in Figure 1. The two supports carry an abutment member in the form of a bar 29 which is formed with a central hole 30 and with two recesses 31 one at each end, the recesses 31 being on opposite sides of the bar. The recessed ends of the bar 29 are engaged in the slots 28 on the supports which serve to carry the bar spaced away from and parallel to the top plate of the casing. It will be appreciated that instead of providing recesses 31 at the end of the bar two transverse slots may be provided, one at each end, the slots opening in opposite directions.

Extending through the hole in the bar 29 is a screwed rod 32 having its head 33 above the bar and carrying a wing nut 34 on that portion of its length located below the bar. A presser plate 35 is screwed on to the end of the rod 32 by means of a tapped boss secured to it. The under surface of the presser member lies, in the operative position of the latter, opposite the upper surface of the top plate of the casing. These two opposed faces constitute clamping faces between which the vulcanizing operation is performed.

In operation, the supports are mounted on the casing, the article to be vulcanized is placed on the top plate 13 and the abutment member is mounted on the supports. The wing nut 34 is then rotated in a counter-clockwise direction as seen from above so as to force the presser member away from the abutment towards the casing so clamping the article between the presser member and the top plate of the casing. It will be seen that

since the wing nut 34 is engaged with the abutment member 29 it will tend to turn the latter with it in a counter-clockwise direction and will tend to force its ends into the slots 28 owing to the disposition of the slots pointed out above. The correct amount of combustible for providing the amount of heat required for one vulcanizing operation is placed in the recess in the lamp.

When spirit is used there is provided a spirit measure which contains just but no more than this amount of spirit, and when solid fuel is used it is provided in pieces of exactly the correct dimensions for providing this amount of heat. The combustible is lit and the lamp placed in position under the casing. The vulcanizing operation will be complete when the combustible has been entirely consumed.

When the vulcanizer is to be of small size for example is intended for vulcanizing cycle or motor-cycle tyres the spirit lamp 15 and the shelves 16 may be omitted. With such a vulcanizer the lid of the tin which contains the solid fuel may be used to support the fuel under the casing.

Referring now to Figure 5, the construction of the casing and the lamp are as described above, except that the casing is much longer and that it is formed with two holes 37 one at each end. The supports 38 are in the form of square rods with short screw-threaded portions 39 and 40 of reduced diameter one at each end. Each support 38 is mounted on the casing with its screw-threaded portion 40 extending through one of the holes 37 and a nut 41 is provided on each support for holding it in position. The abutment member 29 is formed with a central longitudinal slot 42 and two transverse open-ended slots 43 one at each end and opening in opposite directions. These slots engage the screw-threaded portions 39 of the supports and each of the latter carries a wing nut 44 whereby the abutment member may be clamped to the supports. It will be seen that the slots 43 enable the abutment member to be disengaged from the supports without the wing nuts 44 having to be removed.

The presser member 35 has a screwed rod 45 pivotally secured to it at 46 and when in operative position lies opposite a flat boss 47 on the top of the casing. The screwed rod 45 carries a wing nut 34 and in its operative position its free end extends through the slot 42 in the abutment member 29 and the wing nut 34 is below the latter. The operation of this vulcanizer is similar to the operation of the vulcanizer shown in Figure 1.

In a preferred process of patching punctured tubes or tyres employing the vulcanizer described above, the inner tube or tyre is patched with a rubber solution and with a rubber compound over the puncture and placed in the vulcanizer. The solution and

compound are converted into a wax under the influence of the dry heat produced by the combustible, the temperature rising to about 200° Fahrenheit.

5 As the vulcanizer cools the wax hardens and becomes joined to the material of the tyre or tube under the pressure exerted by the vulcanizer which acts as a press. In the case of a tyre a backing of canvas is provided 10 which is joined to the material of the patch as the result of the pressure applied.

The vulcanizers described above may be made of aluminium and preferably have their exposed surfaces highly polished. It will be appreciated that the size of tyre which can be accommodated within the vulcanizer depends upon the distance between the supports and the particular configuration of these supports 24 shown in Figure 1 enables this dimension to be larger than the width of the casing, i. e., enables the casing to be made of less width whilst still allowing of the same size of tyre being handled. It will be appreciated that various modifications may 25 be made in the details of construction described above without departing from the invention. Thus, when the vulcanizer is intended for vulcanizing outer covers the presser members and the upper surface of the casing may both be curved to conform to the curvature of the outer cover.

We claim:

1. A vulcanizer comprising an arched casing, the upper face of which constitutes one 35 face of a clamp for the article to be vulcanized, heating means adapted to be received under the casing in a position to heat the upper portion of the arch, an abutment member, two upstanding supports for the abut- 40 ment member, means for detachably mounting the supports on the upper portion of the arch, means for detachably mounting the abutment member on the free ends of the supports, a presser member having a face 45 opposed to the upper face of the arch, a screwthreaded press rod carried by the presser member, and a nut movable on the press rod between the abutment and the presser member and adapted to co-act with said abut- 50 ment for forcing the presser member towards the upper face of the arch to clamp the article to be vulcanized.

2. A vulcanizer comprising an arched casing, the upper face of which constitutes one 55 face of a clamp for the article to be vulcanized, heating means adapted to be received under the casing in a position to heat the upper portion of the arch, an abutment member which is in the form of a bar and has 60 two transverse recesses, one at each end, opening in opposite directions, two upstand- 65 ing supports for the abutment member which supports two open-ended slots, one at the upper end of each thereof, opening in opposite directions for receiving each a recessed

end of the abutment member, means for mounting said supports on the upper part of the arch, a presser member having a face opposed to the upper face of the arch, a screwthreaded press rod carried by the presser member, and a nut movable on the press rod between the abutment and the presser member and adapted to co-act with said abutment for forcing the presser member towards the upper face of the arch to clamp the article to be vulcanized.

3. A vulcanizer comprising an arched casing, the upper face of which constitutes one face of a clamp for the article to be vulcanized, heating means adapted to be received under the casing in a position to heat the upper portion of the arch, an abutment member which is in the form of a bar and has two transverse recesses, one at each end, opening in opposite directions, two upstanding supports for the abutment member which supports have two open-ended slots, one at the upper end of each thereof, opening in opposite directions for receiving each a recessed end of the abutment member, the lower ends of which supports are bent at right angles to their length to lie substantially parallel to the abutment member, means for detachably attaching said lower ends to the upper portion of the arch, a presser member having a face opposed to the upper face of the arch, a screwthreaded press rod carried by the presser member and a nut movable on the press rod between the abutment and the presser member and adapted to co-act with said abutment for forcing the presser member towards the upper face of the arch to clamp the article to be vulcanized.

4. A vulcanizer comprising in combination an arched casing, the upper face of which constitutes one face of a clamp for the article to be vulcanized, a heating lamp, means on the casing for receiving the lamp in a position to heat the upper portion of the arch, a presser member having a face opposed to the upper face of the arch, a screwthreaded press rod carried by the presser member, an abutment member in the form of a bar having between its ends a hole into which the press rod extends, upstanding supports for the abutment member, means for mounting the supports detachably on the casing, means for mounting the abutment member detachably at each end on the supports to extend parallel to but spaced away from the upper surface of the casing, and a nut movable on the press rod between the abutment and the presser member and adapted to co-act with said abutment for forcing the presser member towards the upper face of the arch to clamp the article to be vulcanized.

5. A vulcanizer comprising an arched casing, the upper face of which constitutes one face of a clamp for the article to be vulcanized, shelves formed in the interior of the

arch, a detachable heating lamp adapted to be received on the shelves to slide thereon into a position to heat the upper portion of the arch, interlocking projections and recesses formed on the lamp and the shelves for resisting endwise displacement of the lamp along the shelves from its operative position, an abutment member carried by said casing and situated opposite to but spaced away from the upper face of the casing, a presser member having a face opposed to the upper face of the arch, a screwthreaded press rod carried by the presser member, and a nut movable on the press rod between the abutment and the presser member and adapted to co-act with said abutment for forcing the presser member towards the upper face of the arch to clamp the article to be vulcanized.

6. A vulcanizer comprising an arched casing, the upper face of which constitutes one face of a clamp for the article to be vulcanized, shelves formed in the interior of the arch, a detachable heating lamp having an open recess to receive the combustible, which lamp is adapted to be received on the shelves to slide thereon into a position to heat the upper portion of the arch, and has an inwardly directed flange around the recess adjacent to but below the top thereof with its material between the flange and the top of the recess undercut, an abutment member carried by said casing and situated opposite to but spaced away from the upper face of the casing, a presser member having a face opposed to the upper face of the arch, a screwthreaded press rod carried by the presser member, and a nut movable on the press rod between the abutment and the presser member and adapted to co-act with said abutment for forcing the presser member towards the upper face of the arch to clamp the article to be vulcanized.

7. A vulcanizer comprising an arched casing, the upper face of which constitutes one face of a clamp for the article to be vulcanized, shelves formed in the interior of the arch, a detachable heating lamp adapted to be received on the shelves to slide thereon into a position to heat the upper portion of the arch, an abutment member, two upstanding supports for the abutment member, means for detachably mounting the supports on the upper portion of the arch, means for detachably mounting the abutment member on the free ends of the supports, a presser member having a face opposed to the upper face of the arch, a screwthreaded press rod carried by the presser member, and a nut movable on the press rod between the abutment and the presser member and adapted to co-act with said abutment for forcing the presser member towards the upper face of the arch to clamp the article to be vulcanized.

8. A vulcanizer comprising an arched casing, the upper face of which constitutes one

face of a clamp for the article to be vulcanized, heating means adapted to be received under the casing in a position to heat the upper portion of the arch, an abutment member which is in the form of a bar and has two transverse recesses, one at each end, opening in opposite directions, two upstanding supports for the abutment member, which supports have two open-ended slots, one at the upper end of each thereof, opening in opposite directions for receiving each a recessed end of the abutment member, the lower ends of which supports are bent at right angles to their length to lie substantially parallel to the abutment member, a slot formed in the bent lower end of each support, two pins provided on the upper portion of the arch in position to pass through the slots in the lower ends of the supports and carrying the supports in position on the arch, a screw-threaded press rod carried by the presser member and a nut movable on the press rod between the abutment and the presser member and adapted to co-act with said abutment for forcing the presser member towards the upper face of the arch to clamp the article to be vulcanized.

9. A vulcanizer comprising an arched casing, the upper face of which constitutes one face of a clamp for the article to be vulcanized, heating means adapted to be received under the casing in a position to heat the upper portion of the arch, an abutment member, two upstanding supports, the lower ends of each of which supports is bent over at right angles to its length and is formed with a slot, two pins provided in the upper portion of the arch in position to pass through the slots and carry the supports in position in the casing, means for detachably mounting the abutment member on the free ends of the supports, a presser member having a face opposed to the upper face of the arch, a screw-threaded press rod carried by the presser member, and a nut movable on the press rod between the abutment and the presser member and adapted to co-act with said abutment for forcing the presser member towards the upper face of the arch to clamp the article to be vulcanized.

10. A vulcanizer comprising an arched casing, the upper face of which constitutes one face of a clamp for the article to be vulcanized, heating means adapted to be received under the casing in a position to heat the upper portion of the arch, an inverted U-shaped yoke, the free ends of the side limbs of which are bent at right angles to the direction of length of the limbs to lie parallel to the cross member of the yoke and are formed with slots, two pins provided on the upper portion of the arch in position to pass through the slots and detachably carry the yoke in position in the arch, a presser member having a face opposed to the upper face of the arch, a screw-threaded press rod carried by the presser member, and

a nut movable on the press rod between the cross-member and the presser member and adapted to co-act with said cross-member for forcing the presser member towards the upper face of the arch to clamp the article to be vulcanized.

In testimony whereof we have signed our names to this specification.
